BAG FOR BALLET SLIPPERS AND LEOTARD

Leonard R. Treinis, Valley Stream, N. Y.

Application March 15, 1955, Serial No. 35,045

Term of patent 7 years

(Cl. D58—2)

The figure is a front view of a bag for ballet slippers and leotard, showing my new design. The rear view of the bag, not shown, is the same as the front view shown.

The characteristic features of my design for the bag for ballet slippers and leotard disclosed reside in the stripes which run lengthwise of the bag having the configurations and arrangement shown.

The drawing is shaded to indicate contrasting color.

I claim:

The ornamental design for a bag for ballet slippers and leotard, substantially as shown and described.
